COMBINED SQUEEZE BOTTLE AND TOOTHBRUSH PACKAGE

Willis W. Sanders, 524 15th St.,
Santa Monica, Calif. 90402

Filed Oct. 4, 1972, Ser. No. 294,961

Term of patent 14 years

Int. Cl. D9—01

U.S. Cl. D9—10

Fig. 1.

Fig. 2.

Fig. 3.

Fig. 4.

Fig. 5.

FIG. 1 is an elevational view of a combined squeeze bottle and toothbrush package showing my new design;

FIG. 2 is an elevational view looking from the right of FIG. 1;

FIG. 3 is an elevational view showing the side opposite that seen in FIG. 1;

FIG. 4 is a top plan view; and

FIG. 5 is a bottom plan view thereof.

I claim:

The ornamental design for a combined squeeze bottle and toothbrush package, substantially as shown.
